United States Patent Office

Des. 180,037

Patented Apr. 9, 1957

180,037

BOTTLE CARRIER

Frank Singiser, Brightwaters, N. Y.

Application May 27, 1954, Serial No. 30,688

Term of patent 14 years

(Cl. D58—4)

Fig. 1.

Fig. 2.

Fig. 3.

Fig. 1 is a front perspective view of a bottle carrier embodying my new design;

Fig. 2 is a side elevational view taken from the right side of Fig. 1; and

Fig. 3 is a rear elevational view thereof.

I claim:

The ornamental design for a bottle carrier, substantially as shown.
